APPARATUS WITH LOCKING DEVICE AND
PRESSURE ACTUATED BUTTON FOR THE
DELIVERY OF PRODUCTS OF TOBACCO
AND OTHER CYLINDRICAL GOODS

Franz Duhan, Vienna, Austria

Application February 16, 1933, Serial No. 656,998
In Austria March 10, 1932

1 Claim. (Cl. 312—78)

Devices are known which deliver single cigarettes and the like when actuated by buttons, handles, levers and so on.

For appliance to automobiles devices are also constructed which are connected with the compressor and the batteries of automobiles to enable the delivery of lighted cigarettes.

The known devices of this kind, however, are extensive, expensive, need special adaption and besides that do not function to perfect satisfaction, as inconveniences and operating troubles can occur with them.

In the said devices the single cigarette falls vertically by its own weight upon an oblique surface and finally arrives in a delivering channel.

All devices of the above mentioned kind have furthermore the disadvantage that they can easily be stolen and when actuated, deliver cigarettes or other goods to every one, for instance to garage attendants.

The apparatus according to the invention, constructed principally for automobiles is simple, cheap and can be shut by a lock in such a manner that first of all the receptacle of goods becomes inaccessible. Furthermore the said lock automatically blocks the press button serving for the delivery of goods so that it is impossible for any unauthorized person to obtain cigarettes. Besides that the mentioned lock prevents theft of various other accessories on the outside of the apparatus, for instance lighter, ash tray and the like which can be removed, when the apparatus is closed without being locked. The apparatus is arranged in close proximity to the driver's seat to enable the driver to take out single cigarettes easily by mere actuation of the press button as well as to make use of the lighter.

The invention comprises a magazine closed by a plate and guided in a casing. In its end position the magazine is fixed by a simple snap. The opening of the unlocked apparatus for the purpose of filling up the magazine takes place by actuation of the snap, which merely in its position of rest secures the magazine by a tapet against movement in the casing.

According to the invention a lever is operated by actuating the press button, which lever dis- places a pivoted closure of the magazine, so that a cigarette falls into the delivery channel. When the button is freed, it flies back under the action of its draw spring, which was extended by pressing in the button and the cigarette is thereby moved forward so far from the de-

livery channel, by means of a pusher disposed on the lever, that it projects and can be taken out. Still before the cigarette begins to be moved forward, the magazine is closed again by the pivoted closure.

The lighting of the cigarette can be effected by simple manipulation of the lighter.

The screws or other means serving for fastening the apparatus are only accessible if the apparatus is opened.

The lock is disposed on the movable magazine in the casing. When the lock is actuated, bolts enter the casing, so that the magazine is fixed in the casing. Such bolts for instance engage the lighter and fasten the same or hinder the movement of the lever, or the actuation of the pressure button. Furthermore an ash tray, which is arranged on the cover and may be taken off, when the unlocked apparatus is opened, but is secured against theft during the locked state of the apparatus, as the ash tray can only be taken off, when the apparatus is opened, or when the magazine is drawn out.

Fig. 1 is a side view of the apparatus in its closed and locked state.

Fig. 2 is a plan view.

Fig. 3 shows the cover plate in front elevation.

Fig. 4 is a cross section through the casing and magazine.

Fig. 5 represents a cross section through the lock.

Fig. 6 illustrates the receptacle for the goods and the elements for their delivery.

Fig. 7 shows the lever and the pressure button serving to deliver the goods and

Fig. 8 the opened lighter disposed on the cover plate.

The cylindrical casing 1 is fixed by its flange by fastening means 3 (screws or the like) on the dashboard 2 of the automobile. The casing has 40 guide ribs 4 for the receptacle 8 which may be moved in axial direction.

The receptacle is rigidly connected with the cover plate 9 which in its closed state renders the fastening means 3 inaccessible. The cover plate 9 is engaged by a snap 5 connected with a leaf spring 6 fixed at 7 in the casing. The receptacle 8 has an axle 10 for the pivoted closure 11 which causes the delivery of the goods. The swinging movement of said pivoted closure in 50 the direction of arrow around the axle 10 is effected by the lever 12 which supports the press button 16.

When the apparatus is unlocked, the cover plate 9 with the magazine 8 may only be drawn

out by pressing down the snap 5. It is furthermore possible with the aid of the slot 39 in the cover plate 9 to displace the ash tray 37 until the pins 40 stand over the circular openings in 5 the slots 41 whereupon it may be taken off.

When the press button 16 is depressed it shifts the lever 12 on the surface 21 of which the press button is rigidly mounted. The lever is guided by corresponding channels, listels or the 10 like (18).

The movement of the lever 12 tensions a draw spring 17 and the oblique surface 13 of the lever 12 engages with a pivoted closure 11 which is caused thereby to swing around an axle 10 in 15 the direction of arrow so that a cigarette 45 may fall into the channel of the magazine 8.

When the press button 16 is freed, it flies back under the action of the spring 17, the oblique surface 13 disengages from the closure 11 and 20 the latter returns into its locking position under the action of a spring 19. The cigarette 45 in the delivering channel is pushed forward in the direction of arrow by a pusher 14, which is mounted on the lever 12 and slides in the delivering channel. The cigarette may be taken out 25 through the opening 46 in the cover plate 9.

The magazine 8 together with the cover plate 9 rigidly connected thereto may be drawn out from the casing 1 after pressing down the snap 5, and refilled with cigarettes. When the snap 30 is pressed down, the leaf spring 6 connected to the casing at 7 is bent and consequently stressed and in this position the snap can pass through the cover plate which, being rigidly connected 35 with the magazine, is positively guided.

When the magazine is pushed into the casing, the leaf spring 6 again extends and a catch disposed on the snap hinders the magazine from being drawn out.

40 The lock (Fig. 5) consists of a lever 32 which may be turned by the bit 33 of a key 34 and thus actuates two slidable levers 25 and 26 by means of pins 30 and 31 disposed on the lock lever 32. The slidable levers are provided with bolts 22 45 and 23 and guided on guide pins 27 and 28 engaging in slots 29 in these slidable levers.

The ash tray has a pin 38 which engages in a 50 hole in the casing 1 and a slot 39 in the cover plate 9. The ash tray is secured on the cover plate 9 by means of the two pins 40 disposed on the cover plate and engaging in slots 41 in the rear wall of the ash tray.

When the locking device is actuated, that is to say when the apparatus is locked in its closed

state, the bolts 22 and 23 engage in holes 24 in the casing. The bolt 22 stops also the movement of the surface 21 of the lever 12 so that the actuation of the press button and the delivery of the cigarettes are hindered. The bolt 23 engages in holes 42 and 43 in the corresponding parts 35 and 36 of the lighter, thus hindering the removal thereof. As, when in locked state the pin 38 of the ash tray lies in a hole in the casing 1 and therefore prevents the turning of 10 the ash tray, the same too cannot be removed:

What I claim is:

A locking device for cigarette delivering machines with smoking requisites, especially for motor vehicles, comprising in combination a 15 flanged cylindrical casing, having two holes in opposite sides of its wall and a hole in its flange, a magazine slidable in said casing, a cover plate fixed on said magazine and adapted to close said casing, a lock on said casing including two 20 bolts adapted to engage in said holes to lock said cover in closed position on said casing, slidable levers each carrying one of said bolts, and a two armed lever hingedly connected at each end to one of said slidable levers, a key adapted to rotate said lever to shift said bolts through the intermediary of said slidable levers, a delivery lever shiftable in said casing, a press button fixed on said delivery lever and projecting from said cover plate adapted to shift said delivery 25 lever in said casing, an abutment on said delivery lever, one of said bolts adapted in locked position to project into the path of said abutment and prevent the shifting of said delivery lever, said cover plate having an aperture and 30 slots, a lighter comprising a body and a cover inserted when not in use in the aperture in said cover plate and having registering holes in its body and cover, the second of said bolts adapted in locked position to engage in the holes of said 35 lighter cover and body to secure said lighter in said cover plate, an ash tray on said cover plate, two pins projecting from the rear wall of said ash tray adapted to engage in two of the slots in said cover plate to allow the partial rotation of said ash tray to secure said ash tray to said cover plate, and a third pin on the rear wall of said ash tray and extending through the third slot in said cover plate, said turned pin adapted when said cover plate is in closed position to engage in the hole in the flange of said casing to prevent the turning and removal of said ash tray from said cover plate.

FRANZ DUHAN.
